EXTENSIBLE TABLE

Application filed May 6, 1929. Serial No. 360,758.

The present invention relates to extensible tables, and is particularly concerned with tables having extensible sections adapted to be carried beneath the table top, or automatically moved out into position to form an extension of the table top.

The extensible tables of the prior art, so far as we are aware, are provided with tops which are not fixedly secured to the table frame, but which must be moved upward relative to the table frame to permit the extensions to slide out into place, after which the table top is dropped down level with the extension. The necessity for simultaneously lifting the table top and also moving the extensions beneath it, make such devices difficult to operate without pinching the fingers or marring the extensions, and one of the objects of the present invention is the elimination of the foregoing difficulties and the provision of a table with extensions and guide mechanism whereby the extensions may be automatically moved out and leveled with the table top, or the reverse, by merely applying force to the extension.

Another object is the provision of an improved commercial form of the table shown in our prior application, Serial No. 268,165, filed April 7, 1928, and an improved and simplified form of guiding mechanism for extensible table tops.

Another object is the provision of an improved extensible table construction in which the extensions are provided with means for concealing the extension mechanism so that the extensible table may be constructed with the same attractive appearance accomplished in the case of tables not having extensions.

Another object is the provision of an extremely simple and sturdy slide mechanism for extensible tables or for other purposes, which embodies a minimum of moving parts and which may be manufactured at an extremely low cost.

Other objects and advantages of the invention will be apparent from the following description and from the accompanying drawings, in which similar characters of reference indicate similar parts throughout the several views.

Referring to the drawings, of which there are three sheets:

Fig. 1 is a plan view of the extensible table, with a part of the top broken away to show the mechanism of the slideable extensions; 55

Fig. 2 is a side elevation with a part of the table in section, on the plane of the line 2—2 of Fig. 1, with a section extended;

Fig. 3 is a similar sectional view taken on the plane of the line 2—2 of Fig. 1, with the sections carried beneath the table top. 60

Fig. 4 is a view in perspective of a guide plate which forms a part of the guide mechanism.

Fig. 5 is a view similar to Fig. 1, of a modified form of table in which the extension is of the same width as the table top; 65

Fig. 6 is a vertical sectional view taken on the plane of the line 6—6 of Fig. 5;

Fig. 7 is a similar view of the same modification, with the extensible top sections in the folded position; 70

Fig. 8 is an end view of the table shown in Fig. 7;

Fig. 9 is a full size detailed view of the slide mechanism for moving the extensible sections automatically from one position to the other, with the parts in the position which they assume just after the sliding out of the extension and before the raising of the extension to a position level with the table top; 75 80

Fig. 10 is a similar view of the same mechanism just after the extension has been pulled out to the limit of its outward movement in the moving of an extension to the extended position; 85

Fig. 11 is a similar view showing the extensible section in an intermediate position, during its movement from its extreme outer position to the position where it forms an extension of the table top; and 90

Fig. 12 is a similar view of the mechanism with the table extensions in extended position, level with the table top and immediately adjacent thereto. 95

Referring to Figs. 1 to 3, 20 indicates the extensible table in its entirety, and the table is preferably provided with a supporting frame indicated in its entirety at 21, a table top 22 fixedly supported upon the frame 21, and one 100

or more extensions or extensible sections 23 and 24 adapted to be located beneath the table top 22 as shown in Fig. 3, or automatically moved to the position shown in Fig. 1, where the extensions form a continuation of the table top.

The supporting frame 21 may consist of a plurality of transverse wooden frame members 25, 26, 27 and 28 joined to side frame members 29 and 30, the side frame members also being adapted to form aprons depending from the table top 23 and adapted to enclose the mechanism for guiding the extensions, as well as enclosing the extensions themselves when in the folded position. The transverse frame members 26 and 27 are located adjacent the top of the side frame members 29 and 30, immediately below the table top 22, thereby providing a support for a longitudinally extending frame member 31 secured to the frame members 26 and 27, preferably midway between the sides of the table and adapted to form a support for the guiding mechanism, and to act as a guide for frame members 32 and 33 carried by one of the extensions 24.

As contrasted with the devices of the prior art, in which table extensions may be concealed beneath the table top, the table top 22 may be fixedly secured to the supporting framework 21, since the extensible sections 23 and 24 are connected to the framework 21 with slide mechanism for automatically moving the sections out into extended position, without the necessity for lifting the top 22 to permit the sections to be moved out. It should be understood, however, that if desired, the top 22 may be made removable for other purposes.

The supporting framework 21 may be provided with legs 34 and 35 of the extended pedestal type, as shown in Figs. 2 and 3, or if desired, the framework may be supported upon legs of any conventional type.

In the embodiment shown in Figs. 1 to 3, the extensible sections 23 and 24 are slightly narrower than the table top 22 so that the extensions 23 and 24 may be provided with depending aprons or side frame members 36 and 37 and an end frame member 38 of substantially the same appearance as the side frame members 29 and 30 carried by the top 22. Thus the side frame members 29 and 30 may extend the full length of the table top 22, and the extensions 23, 24 with their side frame members are adapted to be slidably received between the side frame members 29 and 30.

In the embodiments shown in Figs. 5 to 8, inclusive, the extensions 23 and 24 are made of substantially the same width as the table top 22, so that the extended table is substantially rectangular in form, but in such case, it is necessary to provide the side frame members 29 and 30 with cutouts or slots as at 39 extending from each end of the table to a

point adjacent the transverse frame members 26 and 27.

In the latter embodiments, the extensible sections 23 and 24 need not be provided with the depending apron or side frame members 36, 37 and 38, and the extension mechanism is concealed entirely, only when the extensions are in the folded position shown in Fig. 8.

Referring again to Figs. 1 to 3, the longitudinal frame member 31 may be joined with the transverse frame member 25 by a vertically extending frame member 40 and the longitudinal frame member 31 is adapted to provide a support for a pair of guide plates 41 and 42.

The guide plates 41 and 42 comprise flat pieces of sheet metal having laterally projecting lugs 43 or 44, and the guide plates 41, 42 are secured to the frame member 31 by screws or other fastening means so that the lugs 43, 44 project from the opposite sides of the frame member 31.

The extension 24 may comprise a member of substantially the same thickness as the table top 22 and adapted to form a continuation thereof, and in the present embodiment, the extension 24 is provided with the side and end frame members 36, 37, 38, forming an apron for concealing the slide mechanism.

The extension 24 is fixedly secured to a pair of inwardly projecting frame members 32 and 33 extending at right angles to the edge of extension 24, which is to be located adjacent table top 22. The frame members 32, 33 extend parallel to each other, and are spaced sufficiently to slidably receive the frame member 31 of the table between the frame members 32 and 33.

The frame members 32 and 33 are formed with offset end portions 45, 46, the offset between the main body portion 47 and 48 of the frame members 32 and 33 and the ends 45, 46 respectively, being equal to the distance between the lower surface of the table top 22 and the lower surface of the frame members 26.

It will thus be observed that when the extensible section 24 is located in the position of Figs. 1 and 2, the offset ends 45, 46 of frame members 32, 33 engage below the transverse frame members 26 when the upper surface of the frame members 32, 33 adjacent the edge 49 of section 24 engages just below the table top 22. The upper surfaces of the frame members 32, 33 engaging beneath the table top 22, automatically level the section 24 with the table top 22, the section being supported by the sliding mechanism indicated in its entirety at 50, further to be described, and acting upon the lugs 43, 44 of the guide plates 41, 42.

The frame members 32 and 33 are each provided with appropriate slide mechanism indicated in its entirety at 50 and illustrated

in detail in Figs. 9 to 12, each of the slide mechanisms being adapted to engage one of the lugs 43, 44. For this purpose the frame members 32, 33 are cut out as at 51 to receive the slide mechanism 50, and the frame members 32, 33 are rabbeted as at 52 from the slide mechanism 50 to their outer ends, to provide space for receiving the lugs 43, 44 when the extensible section 24 is moved to the position shown in Fig. 3.

Referring to Figs. 9 to 12, the slide mechanism 50 is illustrated in detail, looking downward in Fig. 1 at the frame member 33. The slide mechanism may consist of a hardened metal plate 53, the proportions and shape of which depend principally upon the thickness of the table top and extensible sections. The plate 53 is preferably provided with a laterally projecting inclined flange 54 adapted to act as a camming surface engaging the lug 44 in raising the extension 24 from a position immediately below the table top 22 to a position approximately level with the table top 22.

The guide plate 53 is also preferably provided with a horizontally extending flange 55 adapted to provide a support for the extensible section 25 by means of the lug 44 when the extension is in the position of Fig. 2. The horizontal flange or shoulder 55 is preferably provided with a slot 56, into which the lug 44 may slide when the extension 24 has reached its extended position immediately adjacent the table top, so as to give the extension a greater degree of stability in its extended position.

The guide plate 53 is also provided with a stop flange 57 carried by plate 53 at the lower end of the inclined flange 54 for definitely limiting the movement of the lug 44 relative to guide plate 53, and the guide plate is also provided with a movable member or guide lever 58 pivotally mounted upon a stud or rivet 59 carried by plate 53.

The flange or shoulder 55 is preferably provided with a beveled edge 60, and the pivoted lever 58 with a complementary beveled surface 61, so that when the parts are in the position of Fig. 11, the lug 44 may slide off the lower edge 62 of lever 58, below the lower surface 63 of flange 55, without any substantial jar or noise. At its opposite end from the beveled surface 61, the lever 58 is provided with a point 64 adapted to engage the flange 54 so as to cause the lug 44 to be cammed from the flange 54 to the lower surface 62 of lever 58. The provision of a horizontal lug or plate 44 in conjunction with an inclined flange 54 as shown in Fig. 10, also enables the point 64 to properly guide the lug 44 from the flange 54 along the edge 62 of lever 58.

The lever 58 is preferably shaped to make the end 65 heavier than the pointed end 64 so that the lever 58 is biased to the position

shown in Figs. 9, 10 and 12. The end 65 of lever 58 may be forked as at 66 and provided with an upwardly extending leg 67 adapted to engage the flange 54 when the beveled edge 61 engages bevel 60 of supporting flange 55.

Referring again to Figs. 1 to 3, the extensible section 23 is also provided with a pair of inwardly projecting frame members 68 and 69, the frame members 68 and 69 being located adjacent the lateral edges of the extension 23 in order to prevent their interference with the frame members 32 and 33, carried by extension 24, and in order to utilize the side frame members 29 and 30 or parts carried thereby, as guides for the frame members 68, 69.

The side frame members 29 and 30 may fixedly support an auxiliary transverse frame member 70 which is adapted to support a pair of upwardly projecting blocks 71 and 72 in spaced relation to the side frame members 29 and 30, to leave space for the apron 36, 37 of the extension 23. The blocks 71, 72 are provided upon their upper surface with guide plates 73 of substantially the form shown in Fig. 4, secured thereto by a plurality of wood screws and provided with laterally projecting lugs 74, 75. The laterally projecting lugs 74, 75 are adapted to cooperate with slide mechanism 50 carried by each of the frame members 68, 69 in substantially the same manner as for that previously described for the other end of the table, with the exception that the slide mechanism 50 in the right end of the table faces outward to engage inwardly projecting lugs 74, 75, while at the left end of the table, the slide mechanism faces inward to engage outwardly projecting lugs 43, 44.

The side frame members 29 and 30 are preferably provided with blocks 76, 77 located adjacent the transverse frame member 27 and the transverse frame member 27 may be provided with a pair of downwardly projecting dowel pins 78, 79 adapted to act as guides for the inner ends of the frame members 68, 69. The inner ends 80 and 81 of the frame members 68, 69 are offset vertically from the body portion of said frame members adjacent the extension 23, in substantially the same manner as described relative to the frame members 32, 33.

The transverse frame member 28 may be carried by frame member 70, and the transverse frame member 28 may be cut away at 82 and 83 to provide slots for receiving and guiding frame members 68, 69, and for receiving the apron or side frame members 36, 37 of extension 23. The end frame member 38 of each extension may be cut away as at 84 to form a finger opening to be grasped in moving the extension from one position to the other.

Referring again to the modification shown

in Figs. 5 to 8, the construction and principle of operation of this embodiment is substantially the same, with the exception that the extensions 23, 24 are not provided with 5 depending aprons, and consequently the extensions 23, 24 may be made of the same width as the table top 22, being adapted to be received within the opening 39 between the framework 21 and the table top 22 at 10 each end of the table.

In this embodiment, the framework of the table may be considerably simplified and the framework 21 may be provided at each end with transverse aprons or frame members 15 85, 86 having slots 87, 88 for slidably receiving the frame members 32, 33 and 68, 69, respectively.

When the embodiment of Figs. 5 to 8 is in the folded position of Fig. 7, the ends of 20 frame members 32, 33, 68, 69 are preferably located flush with the end frame members 85, 86, and the table looks substantially like non-extensible tables, except that the top of the table appears to be of double thickness.

25 In order to fill in the space between the extensible sections 23, 24 at the side edge of the table when they are in the folded position of Fig. 7, an auxiliary strip of material 89 may be placed beneath the table top 22 at its outer edge, extending from the frame member 26 to frame member 27 so that the strip 89 lies flush with the extensions 23, 24 when they are in the folded position shown in Figs. 7 and 8. Each of the extensions 23, 24 in this embodiment is also provided with 30 finger openings 90 centrally located in the lower surface of the extensions 23, 24, adjacent each end.

It should also be noted that in the embodiment of Figs. 1 to 3, the side frame members or aprons 36, 37 carried by the extensions 23, 24, are spaced slightly from the outer edges 91 of the extensions, leaving a shoulder 92 below the extensions immediately adjacent the frame members 36, 37. The side frame members 29 and 30 of the table frame 21 are rabbeted at 93 from the frame members 26 and 27, respectively, to the ends of the frame members 29 and 30. The rabbeted portion 93 of the frame members 29 and 30, 45 forms a shoulder for slidably engaging beneath the outer edges 92 of the extensions 23 and 24 for supporting the extensions in folded position beneath the table top 22.

50 55 The operation of the extensible table is as follows.

When the parts of the table of Figs. 1 to 3 are in the position of Fig. 3, with the extensions folded, each extension is supported 60 beneath the table upon the shoulders 93 formed by rabbeting the side frame members 29 and 30 of the table frame 21. The weight of the extensions 23 and 24 is generally such that the inwardly projecting frame members 32, 33, 68, 69 do not over-

balance the extensions, so that the extensions may be supported at their edges 92 upon the shoulders 93, without engagement of the extensions with the lower side of the table top 22. Either extension may then be moved to the position shown in Fig. 2, by merely applying force to the extension at the finger opening 84, the operator pulling outward upon the extension 23.

For example, when a pull is exerted upon the extension 23 at the finger opening 84, the extension 23 may be slid outward horizontally to a point slightly beyond the final position of the extension 23. During this motion, the extension 23 is slidably supported upon the shoulders 93 of the table frame and by engagement of the frame members 68, 69 in the base of the slots 82, 83. When the extension 23 is extended far enough, it is slidably supported on the table frame 21 by frame members 68, 69; the lugs 74, 75 of the slide mechanism progressing on the grooves provided by the rabbets 52 in frame members 68, 69.

Referring to Fig. 9, the slide mechanism for automatically lifting the extensions is here shown in an intermediate position, just after the extension has been slid out beyond its final position, but still in a position substantially parallel with the position shown in Fig. 3. The lugs 74, 75 which correspond to lug 44 in Fig. 9, are then in a position of Fig. 9, and further horizontal motion of the extension 23, by pulling at the finger opening 84, will cause the lugs on the frame to engage beneath the inclined flanges 54 of the slide mechanism 50, the extension being lifted relative to the frame until the lugs reach the position shown in Fig. 10, where they engage the stop flanges 57.

During this movement, the lugs 74, 75 have passed the pointed end 64 of the lever 58 and on release of the extension, the lugs 74, 75 will slide back against the lower side of the point 64 on lever 58 to retain the extension in this extended position.

The extension is now substantially level with the table top, but is spaced therefrom and may be moved into the final extended position immediately adjacent the table top, by pushing inward on the extension 23, during which the mechanism operates as follows.

The lugs 74, 75, corresponding to lug 44 in Fig. 10, are fixed relative to the table top and the lever 58 slides over lugs 74, 75, slightly lifting the extension until the lugs 74, 75 are directly beneath the pivot post 59, after which the weight of the extension causes the lever 58 to pivot counter-clockwise from the position of Fig. 10 to the position of Fig. 11.

The lever 58 is thus moved until its beveled ends 61 engage bevel 60 on flange 55, and the continued inward movement of the extension 23 causes the lever 58 and flange 63 to

slide smoothly over the lugs 74, 75, (corresponding to lug 44 of Fig. 11), until the lugs 74, 75 are finally seated in recess 56, which takes place when the extension 23 engages the edge of table top 22.

It should be understood that some embodiments of the invention need not be provided with the recess 56 for finally determining the position of the extension, but such a recess is advantageous since the lugs 74, 75 may drop into the recesses 56 to retain the extension in its proper position.

The extension 23 is thus supported in extended position by the engagement of the lugs 74, 75 in recesses 56 and at the same time the offset ends 80, 81 of the frame members 68, 69 are engaged beneath the frame member 27, the frame members 68, 69 acting as cantilevers for supporting the extension 23.

When it is desired to fold the extensible table, that is, to move the extensions from the extended position to the position shown in Fig. 3, it is necessary only to pull upon the extension 23, as at the point 84, in which case the curved recess 56 cams up over the lugs 74, 75, and the flange 55 slides outward off the lugs 74, 75.

Since the lever 58 is naturally maintained in the position shown in Fig. 12, by the weighted forked end of the lever, the lugs 74, 75 will not pass backward under the bottom edge 62 of the lever 58, but the lugs 74, 75 will be engaged by the forked end 66 of lever 58, definitely limiting the outward movement of the extension in its return cycle and causing the lugs to move in a path which is not the reverse of their path previously described in extending the table.

After the lugs 74, 75 have engaged in the forked end 66 of lever 58, the lever 58 will pivot counter-clockwise and the frame members 68, 69 will drop downward until they are supported by the base of the slots 82, in the frame member 28, after which the extension may be pushed inward and the edges 92 of the extension will be slidably received upon the shoulders 93 of frame members 29 and 30, the extension moving to the position shown in Fig. 3.

During the operations of sliding the table extensions outward or inward, the extensions are caused to move in a direction parallel to the table top 22 by means of the frame members 68, 69, which are guided in the slots 82, 83 of frame member 28 and by means of the dowel pins 78, 79 and blocks 76, 77.

The operation of the embodiment shown in Figs. 5 to 8 is substantially the same as that previously described, with the exception that the extensions 23, 24 are slidably supported upon the tops of the frame members 29 and 30, instead of upon rabbeted portions of these frame members.

It will thus be observed that we have invented an improved construction of exten-

sible tables, in which the extensions may be automatically moved to the extended position or to the folded position, by merely pushing or pulling upon the extension. In moving the extension to the extended position, it is highly desirable that the extension be moved to a point beyond the edge of the table top, then leveled with the table top and then returned into abutting relation with the edge of the table top in order to avoid any possibility of sliding upward between the edges of the extension and the table top, which would mar the edges of the table top. However, in returning the extension to the folded position, it is necessary only to pull the extension out slightly, after which it drops immediately to its lower position to be slid in under the table top, the extension being supported in spaced relation to the table top by means engaging below the extension, so that neither the extension nor the table top can be marred by the normal operation of the device. It is highly improbable that anyone would pinch the fingers in opening an extensible table of the present construction, since it is necessary only to grasp the table at a point where there is no possibility of pinching, and it is unnecessary to simultaneously lift the top or to use the other hand for securing the extension in its elevated position, since the mechanism automatically levels the extension with the table top and secures it in proper extended position.

The present device is thus capable of being extended or folded, merely by the use of one hand and with the application of a very slight force on the part of the operator.

While we have illustrated a preferred embodiment of our invention, many modifications may be made without departing from the spirit of the invention, and we do not wish to be limited to the precise details of construction set forth, but desire to avail ourselves of all changes within the scope of the appended claims.

Having thus described our invention, what we claim is new and desire to secure by Letters Patent of the United States, is:

1. In an extensible table, the combination of a supporting frame with a table top carried thereby, a movable top extension adapted to be located adjacent the edge of said top to form an extension thereof or below said top, a pair of guide rails fixedly secured to said movable top extension, a guide member carried by said supporting frame, and guide mechanism consisting of a single switch lever carried by said extension for automatically guiding said extension from a position below said top to a position where said extension forms a part of said top.

2. In an extensible table, the combination of a supporting frame with a table top carried thereby, a movable top extension adapt-

ed to be located adjacent the edge of said top to form an extension thereof or below said top, a pair of guide rails fixedly secured to said movable top extension, a guide member carried by said supporting frame, and guide mechanism consisting of a single switch lever carried by said extension for automatically guiding said extension from a position adjacent the edge of said table top to a position below said table top.

3. In an extensible table, the combination of a supporting frame with a table top carried thereby, a movable top extension adapted to be located adjacent the edge of said top to form an extension thereof or below said top, a guide member carried by said supporting frame, an inwardly projecting frame member fixedly secured to said extension, a guide lug carried by said frame, and guide mechanism carried by said inwardly projecting frame member, comprising a pivoted lever and fixed guide surfaces for guiding said extension into extended position.

4. In an extensible table, the combination of a supporting frame with a table top carried thereby, a movable top extension adapted to be located adjacent the edge of said top to form an extension thereof or below said top, a guide member carried by said supporting frame, an inwardly projecting frame member fixedly secured to said extension, a guide lug carried by said frame, and guide mechanism carried by said inwardly projecting frame member, comprising a fixed camming member for raising said extension upon outward movement thereof, and a pivoted lever for raising said extension on reverse movement of said extension.

5. In an extensible table, the combination of a supporting frame with a table top carried thereby, a movable top extension adapted to be located adjacent the edge of said top to form an extension thereof or below said top, a guide member carried by said supporting frame, an inwardly projecting frame member fixedly secured to said extension, a guide lug carried by said frame, and guide mechanism carried by said inwardly projecting frame member, comprising a fixed camming member for raising said extension upon outward movement thereof, a pivoted lever for raising said extension on reverse movement of said extension, and a fixed shoulder for supporting said extension in extended position.

6. In an extensible table, the combination of a supporting frame with a table top carried thereby, a movable top extension adapted to be located adjacent the edge of said top to form an extension thereof or below said top, a guide member carried by said supporting frame, an inwardly projecting frame member carried by said extension, a guide lug carried by said frame, and guide mechanism carried by said inwardly projecting frame

member, comprising a fixed shoulder for supporting said extension in extended position, and a pivoted lever for guiding said lug to said shoulder on inward movement, said lug being adapted to slide off said shoulder on outward movement.

7. In an extensible table, the combination of a supporting frame with a table top, an apron carried by the side of said frame enclosing extension mechanism, an extension having an apron at its sides and end, and automatic mechanism between said frame and extension to guide said extension from a position below said top to extended position, by the application of force to said extension, said mechanism comprising a pair of supporting members carried by said extension, a pair of lugs carried by said frame, and guide plates carried by said supporting members, having flanges to support said extension in extended position, and having a movable member to raise said extension to said position.

8. In an extensible table, the combination of a supporting frame with a table top, an apron carried by the side of said frame enclosing extension mechanism, an extension having an apron at its sides and end, and automatic mechanism between said frame and extension to guide said extension from a position below said top to extended position, by the application of force to said extension, said mechanism comprising a pair of supporting members carried by said extension, a pair of lugs carried by said frame, and guide plates carried by said supporting members, having flanges to support said extension in extended position, and having movable members to raise said extension to said position, and having camming flanges to raise said extension to be supported by said movable members.

9. In an extensible table, a lifting and supporting mechanism comprising a metal plate having a transversely extending lifting flange located at its upper edge and having a transversely extending supporting flange located adjacent its lower edge, a single switch lever pivotally mounted on said plate and having a point adapted to engage said lifting flange to direct a guide lug along the lower edge of said switch lever, the opposite end of said switch lever being adapted to guide said lug underneath said supporting flange.

10. In an extensible table, a lifting and supporting mechanism comprising a metal plate having a transversely extending lifting flange located at its upper edge and having a transversely extending supporting flange located adjacent its lower edge, a single switch lever pivotally mounted on said plate and having a point adapted to engage said lifting flange to direct a guide lug along the lower edge of said switch lever, the opposite end of said switch lever being adapted to guide said lug underneath said supporting flange.

end of said switch lever being adapted to guide said lug underneath said supporting flange, said switch lever having a forked end adapted to guide said lug in a different direction upon reverse movement of said lug from said supporting flange.

5 11. In an extensible table, the combination of a supporting frame with a table top fixedly carried by said frame, a movable top extension adapted to be supported beneath said top or as an extension of said top, said extension being fixedly secured to a pair of guide rails, lifting mechanism for said guide rails, comprising a movable lug and a switch mechanism consisting of a metal plate having a switch lever pivoted at said plate, and an inclined lifting flange carried by said plate, said switch lever having a pointed end adapted to engage said flange and to direct 20 said lug from said flange to the lower side of said switch lever.

12. In an extensible table, the combination of a supporting frame with a table top fixedly carried by said frame, a movable top extension adapted to be supported beneath said top or as an extension of said top, said extension being fixedly secured to a pair of guide rails, lifting mechanism for said guide rails, comprising a movable lug and a switch mechanism consisting of a metal plate having a switch lever pivoted at said plate, an inclined lifting flange carried by said plate, said switch lever having a pointed end adapted to engage said flange and to direct said 25 lug from said flange to the lower side of said switch lever, and a supporting flange adapted to receive and support said lug, said lever being located to guide said lug below said supporting flange.

30 40. In witness whereof, we hereunto subscribe our names this 2nd day of May, 1929.

RALPH MOLINARI.
JOHN BALDI.
